(57) **CLAIM**

The ornamental design for the storage box to hold traffic signs and stands as shown and described.

DESCRIPTION

FIG. 1 is a front perspective view of the storage box to hold traffic signs and stands showing my new design;

FIG. 2 is a left side view thereof;

FIG. 3 is a right side view thereof;

FIG. 4 is a front view thereof;

FIG. 5 is a back view thereof;

FIG. 6 is a top view thereof;

FIG. 7 is a bottom view thereof;

FIG. 8 is a bottom perspective view;

FIG. 9 is a rear perspective view showing an interior view of the storage units; and,

FIG. 10 is a rear perspective view showing the storage box to hold traffic signs and stands on an exemplary vehicle in use.

The broken lines illustrating the vehicle in FIG. 10 represent environment. The remaining broken lines illustrate portions of the article. None of the broken lines form part of the claimed design.

1 Claim, 8 Drawing Sheets
